DEGASSING OF CATHODE RAY TUBES
Leighton E. Griffiths, Newark, N.J.
(18 Cedar St., Pompton Lakes, N.J.)
Filed Aug. 27, 1963, Ser. No. 394,786
11 Claims. (Cl. 313—176)

This invention relates to cathode ray tubes and more particularly to such tubes used primarily as television "picture" tubes.

More particularly the invention deals with getters and diagnosing processes for use with "picture" tubes having laminar faces using plastic adhesives subject to damage at the usual temperatures at which such tubes are degassed.

It is a general object of the present invention to provide a novel combination of getters for use in connection with rebuilding "picture" tubes having laminar faces and novel processes for degassing such tubes at temperatures which do not damage the tube faces.

More particularly, it is an object of the invention to provide getters and procedures which permit the proper degassing and maintenance of sufficiently low gas pressures during the shelf and use life of "picture" tubes even if they are rebuilt in envelopes having laminar faces subject to damage by temperatures much below those normally used during pumping and degassing.

An important object of the invention resides in the use of a plurality of getters in a rebuilt "picture" tube, all of which are mounted on the replacement "gun" assembly, and some of which are flashed shortly after the tube is sealed off and others which are of a character to actively adsorb gases at intermediate temperature ranges during the operation of the tube throughout its life.

Another important object of the invention is to provide for both initial and subsequent degassing of a "picture" tube, following necessary low temperature pump-down, by providing a plurality of different type getters distributed about the "gun," some for degassing immediately subsequent to sealing off and others effective throughout the life of the "gun."

One of the features of the "cold" degassing of a "picture" tube having a face laminated with the use of a plastic adhesive between the two glass laminae is the covering of the tube face with a heat reflective layer enabling inductive heating of the "gun" remotely positioned in the tube neck with damage to the face adhesive.

Another feature of the invention which serves to prolong the useful life of a rebuilt picture tube which has been degassed cold is the provision of a getter of zirconium positioned adjacent to the No. 1 grid of the "gun" which is electronically heated in parallel to the cathode heater. The arrangement being such that the total heater consumption of power is the same as that used by the original heater for the cathode whereby the rebuilt "picture" tube can be used as television sets having all of the tubes connected in a series and known as "string" sets, which avoids the use of a heater transformer. The new cathode is designed to be as effective as the original one although operation is on one-half the original wattage.

Other and further objects and features of the invention will be more apparent to those skilled in the art upon a consideration of the following specification and the accompanying drawings, wherein are disclosed embodiments of the invention with the understanding that such changes and modifications may be made therein as fall within the scope of the appended claims without departing from the spirit of the invention.

In said drawings:

FIGURE 1 is a small scale elevational view, partly in longitudinal section, of a cathode ray tube and illustrating a laminated screen face;

2

FIGURE 2 is an elevation, on an enlarged scale, of an electron gun for use in the neck of a cathode ray tube of the type shown in FIGURE 1 and illustrating several getters in place thereon;

5 FIGURE 3 is a longitudinal central section, on a still larger scale, of the No. 1 grid, cathode and heater assembly of FIGURE 2 illustrating two hot getters in place thereon;

10 FIGURE 4 is an elevation, partly broken away, of a No. 1 grid assembly like that of FIGURE 3 with an added external heated getter mounted thereon; and

15 FIGURE 5 is a view similar to FIGURE 4 but showing a different external heated getter.

Cathode ray tubes of the type known to most television viewers as "picture" tubes have a relatively long life if not damaged or abused but eventually the operation becomes poor due to the reduction in electron emission from the cathode and the picture becomes weak. It may cease altogether resulting from burnout of the cathode heater. Since the glass envelope of the tube is large and heavy it represents with its interior fluorescent screen the major cost item of the finished product and it is thus economically feasible to renew the tube by replacing the electron "gun" assembly in the neck to achieve a new cathode and heater.

20 Relatively large industries have grown up for the manufacture of new "guns" and for the rebuilding of worn-out "picture" tubes. Replacement components and practices had become relatively standardized and well known until the advent of the laminated tube face, produced by adding a second curved glass plate over the integral face of the tube using a sheet of suitable heat-softened plastic as the adhesive in the manner of manufacture of automobile safety glass. This permitted the elimination of the separate protective glass cover for the tube face with the attendant dust collecting and cleaning problems and, to some extent, prevented certain annoying reflections, but added to the rebuilders' problems.

25 When tubes are built new, the problems of degassing them before and after sealing is simplified by their acceptance of heating temperatures of at least 400 degrees C. without damage, so that occluded gases in and on the glass and metal parts are fairly easily pumped out and/or sorbed (adsorbed and absorbed) by more or less standardized practices. However, the presence of the plastic laminant in the new safety front tubes limits the temperature to which the envelope can be safely heated to approximately 80 degrees C. Early attempts to obviate this disadvantage required removal of the extra glass and the laminant. This, however, is costly and the same or another glass front had to be replaced after degassing. The process was found to be uneconomical leading to the development of the present "cold" degassing where the envelope temperature is kept below 80 degrees C. The new process will now be described along with descriptions of the several getters.

30 Referring first to FIGURE 1 of the drawings, 10 illustrates the envelope of a more or less conventional type of cathode ray tube, primarily as used for television viewing, and it is an integral unit having a glass neck 11, a flare or conical portion 12, extending forwardly from the front end of the neck, and a front closure or screen portion 13, the inner surface of which is coated as at 14 with a suitable material which fluoresces when impinged by a cathode ray, from the electron gun in the neck as will be later disclosed. The material of the screen is a suitable chemical which has the property of emitting light when bombarded by electrons. This fluorescence, as it is called, provides for a continued emission of light for a short time after bombardment referred to as phosphorescence. The length

of time that it lasts is referred to as persistence and may vary in accordance with the intended use for the cathode ray tube. In any event, the cost of the glassware plus the formation of the phosphorescent screen represents a large portion of the total cost of a cathode ray tube which is used for television viewing, and the desirability of retaining the portions which do not deteriorate during use has led to what is known as rebuilding, i.e. replacing the cathode ray gun, which, of course, necessitates repumping the vacuum and eliminating undesirable gases from the interior of the tube since these have a deteriorating effect on the action of the emitting material on the cathode and in general on the performance of the whole tube.

The degassing of rebuilt tubes has been complicated by a later development in the manufacture of the envelope. Earlier tubes have merely a glass face at 13 integral with the remainder of the envelope and in order to protect the face against mechanical damage and for safety purposes it was mounted behind a laminated safety glass which formed a portion of the cabinet in which the tube was mounted, but this offered many problems, particularly the accumulation of dust on the face of the tube and on the rear of the safety glass, necessitating removing the chassis on which the tube is mounted for the purpose of cleaning these otherwise inaccessible surfaces. The accumulation of dust is relatively rapid because of the electro-static energization of the tube front.

To eliminate the requirement for separate safety glass and to permit ready cleaning of the front of the tube face, later tubes have been manufactured with a laminated face as shown in FIGURE 1 and a second glass 15, curved like the tube front 13, is bonded thereto by a laminating layer 16 of a suitable plastic material which reinforces the whole laminated face and securely attaches the two glass parts 13 and 15 to each other.

In the absence of the extra pane 15 and the plastic 16, degassing was accomplished more readily by heating the whole glass envelope in an oven to a relatively high temperature of approximately 400 degrees C., which could be done without damaging it. However, the cost of softening the laminate, removing the pane 15 and subsequently replacing it in order to permit degassing after rebuilding, by the use of high temperature heating of the envelope is too costly, and there is a demand 45 for means for degassing tubes without removing the face laminant.

The cathode ray gun 18 illustrated in FIGURE 2 contains substantially all of the components necessary to complete the cathode ray tube, and is mounted within 50 the neck 11 by welding the rear end of the neck to the rim of the glass disc 19 at the base of the gun. The several leads and supports 20 from the various components of the gun extend through presses 21 on the disc, which is tubulated at 22 whereby air and any gases are pumped out during evacuation of the tube, the tubulation is sealed off after as much gas has been pumped out as possible. Thereafter approximate ones of the conductors 20 are attached to contact pins which are mounted in a base secured to the end of the neck of 60 the tube all in a conventional manner.

As viewed in FIGURE 2 the two outermost leads 20 are sufficiently heavy to act as supports for the whole of the gun and they are connected to straps 24 which are secured to and support the inverted cup-like first grid 25 the components of which are shown in greater detail in the section of FIGURE 3. These straps also extend outwardly and are fused into the glass support rods 27 to which are attached straps 28 carrying the second grid 29 and straps 30 supporting the anode 31. This latter is an elongated cylinder usually equipped with a top closure plate having a small perforation and a radiating rim 33 which here is shown supporting a pair of clamps 34, one carrying the plate or strap 35 mounting the cylindrical getter ring 36 above the top of the

anode and having a number of indentations each filled with a getter paste 37 of barium or like material which are adapted to be flashed as by heating the metallic ring 36 inductively at an appropriate time during or following the degassing of the tube. The indentations face radially outwardly to project the getter vapors against the walls of the neck of the cathode ray tube for properly absorbing vapors within and on the surface of the glass of the neck, and the parts of the gun. Mounted above the ring 36 by means of a second clamp mounting wire 38 is the annular getter channel 40, which is U-shaped in cross-section as seen at 41 and contains a barium getter 42 in the bottom of this channel. This second getter is adapted to be flashed simultaneously with getters 37, but the ring is so designed and configured that it projects the vapors from the barium or other suitable material into the flare of the envelope and toward the surfaces of the screen at the front thereof to absorb undesired vapors and gases in a more or less conventional manner.

FIGURE 3 shows, in substantial enlargement, the component of the first grid 25. It will be noted that this is an inverted straight walled metal cup open at the bottom and closed at the top except for a small aperture 44 through which the electron beam is projected from an emissive material 45 mounted on the flat upper end of the cathode cylinder 46 concentric with grid cylinder 25 and positioned a carefully measured distance below the aperture 44 by being supported 30 in a ceramic disc 47 by means of beads 48 and 49 respectively engaging the upper and lower surfaces of the disc. The disc is fitted tightly in the cylinder 25 and supported from beneath by the right angled annulus 50 of metal welded to the grid cup walls. The upper surface of the cathode tube is properly spaced from the top wall of the grid cup 25 by means of the cylindrical sleeve 52 which has an annular foot 53 limiting the insertion of the ceramic disc 47 and with its upper end engaging the said top wall to which it may be secured by welding if desired.

The above features are more or less conventional in certain makes of electron guns and the emissive material 45 on the head of the cathode tube is appropriately heated by a double wound insulated wire helix 55, supported within the cathode tube, and closely spaced from the walls thereof, by means of the leads 56 therefrom which are attached as seen in FIGURE 2 to a pair 23 of the wires which pass through the disc 19. They not only conduct current to the heater but mechanically support it in position within the cathode. The heater wire is appropriately covered with an insulating ceramic material preventing it from short circuiting against the metal cathode tube.

Because of the necessity for degassing a rebuilt cathode ray tube, having the laminated face described above, at temperatures not higher than about 80 degrees C. for the envelope, the getter action must be much more effective than under the old process where the envelope could be heated to as much as 400 degrees C. while the metal parts of the gun were inductively heated sometimes to a low red temperature. The metal parts can also be heated to this temperature in the present construction since they are remote from the tube face.

The getter already described at 37 and 42 are effective at the time of degassing and pump-out to eliminate free gases and air remnants which the pumps have been unable to remove, but there still remain certain small quantities of the sorbed gases on the surfaces, and sometimes below them, of the glass and metal parts of the tube assembly and since the getters already described are flashed but once they have no further action toward eliminating these gases which may be subsequently liberated slowly throughout the life of the tube.

For the purpose of removing these remnant gases the applicant proposes to add what may be termed "hot get-

ters," i.e. those which are heated every time the tube is in use and thus serve throughout its life to continue to absorb any liberated gases and vapors including hydrocarbon vapors from the diffusion pumps. One such getter is shown at 60 surrounding the spacer cylinder 52. It is in the form of a foil or thin metal strip surrounding the spacer 52 and closely secured thereto by welding or the like so that it is heated whenever the heater 56 is energized, by conduction and radiation therefrom. Preferably this getter 60 is titanium metal which when heated to a temperature of about 200 degrees C., readily achieved in the construction shown, becomes an active getter and has a maximum sorbing action for gases such as hydrogen, oxygen, nitrogen and the oxides of carbon. Since the reaction between the getter material and these gases is an irreversible one, any which are liberated, either during the shelf life of the tube before use, or subsequently in operation, or between operations are continuously removed every time the tube is turned on and hence the life of the tube and of the components which might be harmed by these gases is extended to at least equal that of the tubes which could be degassed at the high temperatures mentioned previously in the absence of the laminated front face.

As a further supplement to the titanium getter just described a second hot getter is illustrated at 61 in the form of a sheet of zirconium metal surrounding the end of the cathode tube 46, below the ceramic or porcelain disc 47, and it is also preferably attached by welding to improve the heat conductivity. This material, which will be heated to a temperature of about 800 degrees C. by the cathode heater 55 which it surrounds finds this an optimum temperature for maximum effectiveness and note that the zirconium also absorbs water vapor.

Zirconium strip 61 acts as a hot getter and sorbs gases that would otherwise increase the pressure within the tube enough so that the cathode might be attacked or poisoned during the time the tube is being scanned or the screen excited but by sorbing these gases the vacuum is kept low enough so that the cathode is neither attacked during shelf life nor at other times when the tube is not being used.

The four getters described above including the barium getters 37 and 40, which are flashed after the tube is sealed, and the two hot getters 60 and 61 are usually adequate to give the tube a normal life of the order of about 3,000 hours of use but under some circumstances and as an added precaution against the liberation of undesired gases, which might attack and poison the emissive material of the cathode a fifth getter may be added in the manner illustrated in either FIGURE 4 or FIGURE 5.

Referring to FIGURE 4, the first grid is shown at 25' entirely in elevation and it will be understood that it is equipped with the conventional cathode and heater and with the titanium and zirconium hot getters just described above. In this figure there is illustrated a cylinder 65 of zirconium metal supported by welded wires 66 from the first grid and parallel to its axis and closely adjacent thereto and within this is fitted a heater coil 67 which may be of the same nature as the cathode heater with ceramic insulation on the wire. The tube may be open top and bottom but is preferably closed at the top as shown. The heater has two leads 68 which are connected in parallel to the leads 56', from the cathode heater so that when the cathode heater is in operation the heater 67 will also be energized.

For use with tubes whose heaters are connected in parallel to the heaters of the smaller tubes in the cathode ray television set and all energized from a 6.3 volt transformer secondary, the consumption of additional current by the heater 67 is unimportant, as long as it is within the capacity of the transformer, but where television sets of the "string" type are used with all heaters in series on the usual house voltage of 110 it is highly important that the total current consumption by the heaters in the cathode ray tube is the same in a rebuilt tube as in a new one.

The normal current consumption for a 6.3 volt heater is 600 milliamperes but it has been found that by appropriate design of the cathode, the emitting material, and the cathode heater, 300 milliamperes provide a beam as effective as the normal 600 milliamperes heater and this leaves 300 milliamperes which can be used for heater 67 for the fifth getter, thereby providing a cathode ray tube with a total current consumption of 600 milliamperes to properly fit in the series tube string without upsetting the current and potential available for each of the other tubes therein.

In FIGURE 5 the first grid 25" is arranged and equipped as is the one in FIGURE 4 but the type of getter supported thereby is somewhat different. In this case a ceramic rod 70 is molded about an axial support wire 71 which is bent at right angles and welded at 72 to the wall of the grid so that the rod is parallel thereto as shown, and about this rod is wound a relatively heavy open coil conductor 73 of zirconium wire which is connected in parallel to the conductors 23 leading to the cathode heater so that both are energized in parallel. The zirconium wire 73 can by appropriate design be arranged to assume the most effective temperature at which the metal thereof sorbs gases and vapors from the interior of the tube. It will be appreciated that in the embodiment of FIGURE 5 the zirconium metal is heated immediately on turning on the current and thus acts somewhat more promptly than a zirconium at 61 in FIGURE 3 which is only heated after some delay.

The following schedule is suggested as the procedure for evacuating a rebuilt cathode ray tube having a laminated face plate and fitted with a new electron gun equipped with getters according to the present invention:

Pump the tube for one and a half hours at a temperature of 80 degrees C. for the envelope;

Bomb the gun at a low visible temperature for fifteen minutes (this means inductive heating of the metal in the gun by a coil energized by H.F. alternating current);

Convert the cathode in the usual manner which includes energizing the heater at a higher than normal voltage. This conversion requires heating the cathode sufficiently to convert the barium carbonate on its upper end to barium oxide which occurs at approximately 850 degrees C., requiring a heater voltage of about 13. This same voltage being applied to the heater 67 or 73 for the zirconium getters shown in FIGURES 4 and 5 heats it to a temperature between 880 degrees C. and 1200 degrees C. which at the then existing vacuum of about 10^{-6} results in an excellent clean up of any gases in the zirconium. Later, when the heater voltage is reduced to normal, the zirconium reverts to its ability to absorb about 1500 times its volume of hydrogen (at S T P). Thus, every time the tube is turned on, the zirconium is heated to its best absorptive temperature;

After cathode conversion keep the heater at nine volts and bomb for another ten minutes;

Shut off the bomber and continue pumping for another ten minutes with the heater still on at nine volts;

Tip the tube off;

Remove the tube face up from the oven being careful not to touch the laminated face as the plastic is soft;

Allow the tube to cool in the atmosphere;

Flash the barium getters in the tube neck for approximately 25 seconds;

Then age the tube in the normal manner.

It is suggested that aluminum foil be fitted closely over the face of the tube before pump down is started and that windows should be placed in the dag on the neck of the tube so that the flashing of the barium getters may be watched and properly controlled.

The tube is now ready for use immediately or after a reasonable lapse of time and will have an effective life of as long as a new tube which has been degassed at much higher temperatures.

I claim:

1. An electron gun assembly for replacement use in cathode ray tubes having an envelope temperature limitation of about 80 degrees C. and including a first grid cylinder having a substantially closed upper end, a ceramic disc mounted in said cylinder, a cathode tube secured in and extending through said disc, a heater in said cathode tube, a metal sleeve spacing said disc and the active end of said tube from said closed upper end, a titanium getter strip surrounding and secured to said sleeve, a zirconium getter strip surrounding and secured to said cathode tube below said disc, a barium getter mounted on and above said gun assembly and arranged to be flashed toward the envelope face and side wall, a second barium getter adjacent to the first one and arranged to be flashed toward the envelope neck, a zirconium getter, means mounting said last mentioned getter adjacent to and insulated from said first grid cylinder and means connecting said last mentioned getter in parallel to said cathode heater for simultaneous energization.

2. An electron gun assembly for replacement use in a cathode ray tube having the screen face thereof laminated by the use of a plastic which limits envelope heating to about 80 degrees C. for degassing; said gun including a first grid cylinder of metal having a substantially closed flat upper end and an open bottom; a ceramic disc secured across said cylinder intermediate to its ends; a cathode tube having a closed upper end and an open lower end secured in and extending through said disc; a heater in said cathode tube; a metal sleeve surrounding and spaced from the upper portion of said tube and engaging the disc and said flat upper end of said grid cylinder to space the tube closed end therefrom; a getter strip surrounding and secured to said spacer and comprising a metal effective to absorb residual gases in the tube at a temperature of the order of 200 degrees C.; a second getter strip surrounding and secured to said cathode tube below said disc and comprising a metal effective to absorb gases in the tube at a temperature of the order of 800 degrees C.; getters mounted on and above the gun assembly to be flashed, after the tube is sealed, toward the envelope face, side wall and neck; a metal getter supported near and by and insulated from said grid cylinder and means to continuously heat said getter electrically in parallel to the cathode heater when the latter is energized.

3. An electron gun assembly for replacement use in a cathode ray tube having the screen face thereof laminated by the use of a plastic which limits envelope heating to about 80 degrees C. for degassing; said gun including a first grid cylinder of metal having a substantially closed flat upper end and an open bottom; a ceramic disc secured across said cylinder intermediate to its ends; a cathode tube having a closed upper end and an open lower end secured in and extending through said disc; a heater in said cathode tube; a metal sleeve surrounding and spaced from the upper portion of said tube and engaging the disc and said flat upper end of said grid cylinder to space the tube closed end therefrom; a getter strip surrounding and secured to said spacer and comprising a metal effective to absorb residual gases in the tube at a temperature of the order of 200 degrees C.; a second getter strip surrounding and secured to said cathode tube below said disc and comprising a metal effective to absorb gases in the tube at a temperature of the order of 800 degrees C. and getters mounted on and above the gun assembly to be flashed, after the tube is sealed, toward the envelope face, side wall and neck.

4. An electron gun assembly for replacement use in a cathode ray tube having a screen face subject to a maximum temperature limit of about 80 degrees C. when de-

gassing; said gun including in addition to conventional flash getters used after pumping, at least two low temperature getters effective throughout the life of the tube whenever it is in use; a first grid incorporated in said gun and including a metal cylinder having a closed upper end and an open lower one; a ceramic disc secured across said cylinder intermediate its ends; a metal cathode tube having a closed upper end and an open lower end secured in and extending through the center of said disc; a metal sleeve surrounding and spaced from the upper portion of said cathode tube and engaging the disc and the upper end of said grid cylinder to space the tube closed end accurately from said upper end of said grid cylinder; a heater in said cathode tube; one of said low temperature getters surrounding and engaging the portion of said cathode tube beneath said ceramic disc and the second low temperature getter surrounding and engaging the said spacer sleeve.

5. The electron gun assembly as defined in claim 4 in which said low temperature getter on the cathode tube is of a material most effective to sorb gases when operated at a temperature of the order of 800 degrees C. and the second low temperature getter being of material most effective to sorb gases when operated at a temperature of the order of 200 degrees C.

6. The electron gun assembly as defined in claim 4 in which the getter on the cathode is a thin sheet of zirconium welded to said cathode tube and the getter on the spacer sleeve is a thin sheet of titanium welded to said spacer sleeve.

7. The electron gun assembly as defined in claim 4 in which a further getter is supported adjacent said first grid and comprised of a metal having the gettering properties of zirconium and means connected in parallel to said cathode heater to heat said further getter during operation of the cathode ray tube.

8. An electron gun assembly for replacement use in a cathode ray tube having a screen face limited to a maximum temperature of 80 degree C. when degassing and including a first grid, in the form of an inverted metal cup, a ceramic disc secured across said cup intermediate its length, a cathode cylinder extending axially through said disc, a heater in said cylinder, a metal sleeve larger than said cylinder and smaller than the cup spacing the disc from the closed upper end of the cup and a strip of getter metal secured to the outer surface of said sleeve and effective to sorb gases from the cathode ray tube interior at the temperature to which it is heated by the said cathode cylinder heater.

9. The electron gun assembly as defined in claim 8 in which said getter metal is titanium and the temperature is of the order of 200 degrees C.

10. The electron gun assembly as claimed in claim 8 including a second getter outside of said metal cup and means in parallel to said cathode heater to heat said second getter during tube use.

11. The electron gun assembly as defined in claim 10 in which the cathode and getter heater means have a total current consumption of the cathode heater alone in the original gun in the cathode ray tube.
